UNITED STATES PATENT OFFICE.

ALPHONSE KING, OF CHICAGO, ILLINOIS.

DESIGN FOR AN ADVERTISING-FRAME.

SPECIFICATION forming part of Design No. 27,404, dated July 20, 1897.

Application filed May 27, 1897. Serial No. 638,474. Term of patent 14 years.

To all whom it may concern:

- Be it known that I, ALPHONSE KING, a citizen of the United States, and a resident of Chicago, in the county of Cook and State of Illinois, have invented and produced a new and original Design for Advertising-Frames, of which the following is a specification, reference being had to the accompanying drawing, forming part thereof.
- 10 The drawing is a front elevation of an advertising-frame, showing my new design.
- My invention relates to an advertising-frame containing illuminated panels and advertising-spaces.
- 15 The said design consists of a frame in substantially the form of a portico and comprising a suitable base, columns, and gable. The gable is surmounted by finial and other ornaments, and in the pediment is located a clock. The main body of the frame is divided up by vertical and horizontal strips into squares, some of which are closed by dark-colored glass, so as to form a series of over-

lapping Maltese-cross figures and checker-board figures, in the centers of which are 25 formed in light lines likenesses or other pictorial representations, while the intermediate squares are filled with light-colored glass, or these colors may be reversed and the Maltese-cross figures and checker-board figures 30 made of light-colored glass, while the intervening squares are of dark-colored glass. At the respective ends of the ornamental groundwork thus formed are located two advertising-spaces divided into a number of panels for 35 the introduction of advertising-cards, &c.

Having thus described my invention, the following is what I claim as new therein and desire to secure by Design Letters Patent:

The design for an advertising-frame substantially as herein shown and described.

ALPHONSE KING.
